PUMPING JACK OIL MAKEUP AND
PRESSURE CONTROL

Fred H. Rued, Lafayette, Calif., assignor to The
Pelton Water Wheel Company, San Francisco,
Calif., a corporation of California

Application May 16, 1950, Serial No. 162,221

7 Claims. (Cl. 60—52)

1

My invention relates to pumping jacks for use generally in connection with pumping deep oil wells and is particularly concerned with a pumping jack of the general type shown in the patent of Kyle and White, 2,325,138, issued July 27, 1943 and in the co-pending application of Ira Morgan White, Serial No. 32,629 filed June 12, 1948 and entitled Hydraulic Pumping Jack Control, now Patent No. 2,617,256, and in the co-pending application of Ira Morgan White, Serial No. 114,180 filed September 6, 1949 and entitled Hydraulic Pumping Jack Now Patent No. 2,575,241.

In hydraulic pumping jacks of this type there is a balancing tank designed to receive a quantity of oil and a quantity of air both under pressure. The oil from the balancing tank is transferred by a force pump to a cylinder and piston arrangement which actuates the pump. The oil transfer proceeds alternately in opposite directions under the control of a reversing valve. In common with most hydraulic machinery, various leakages and oil spillages occur during the operation of the structure. It is quite necessary to maintain a supply of oil in the balancing tank and preferably the supply of oil is maintained substantially at a fixed amount despite losses from the system.

It is therefore an object of my invention to provide a mechanism for supplying to the balancing tank an amount of oil to make up for escaped and leakage oil.

Another object of my invention is to provide means for maintaining a pre-determined level of oil in the balancing tank.

A still further object of my invention is to provide means for maintaining in the balancing tank a pre-determined amount of oil and a volume of air under pre-determined pressure.

A still further object of my invention is in general to improve hydraulic pumping jacks.

An additional object of my invention is in general to improve pumping jack oil make-up and pressure controls.

Other objects, together with the foregoing, are attained in the embodiment of my invention described in the accompanying description and illustrated in the accompanying drawing.

The drawing is a diagrammatic representation of a pumping jack oil make-up and pressure control in its usual environment in a pumping jack of the nature identified. Parts of the figure are broken away to reduce its size and complexity and certain parts are illustrated in cross section on planes of symmetry.

While the pumping jack oil make-up and pressure control of my invention can be incorporated

in various different ways depending upon surrounding circumstances and can be modified within wide limits to accommodate itself to various different engineering requirements, it has successfully been operated in accordance with the present disclosure. In this arrangement there is provided a hydraulic pumping jack cylinder 6 usually arranged vertically and having a piston therein (not shown) connected by a piston rod 7 to a hydraulic pump at the bottom of a well (not shown).

In order that the piston may be reciprocated within the cylinder 6, there is afforded a source of operating pressure in the nature of a main oil pump 8 diagrammatically shown, and driven in any suitable way by a driving shaft 9. The pump 8 is provided with a pair of inlet openings 11 and 12 and an outlet 13. The pump is preferably of the positive displacement type and operates continuously. The pump inlets 11 and 12 are connected by a manifold 14 leading to spaced ports 16 and 17 in a reversing valve generally designated 18. The outlet 13 of the pump is likewise connected by a duct 19 to a central port 21 in the reversing valve 18.

Within the reversing valve is a valve shuttle 22 having an appropriate contour so that it can be shifted axially between one extreme position, illustrated, and an opposite extreme position in order to provide various interconnections. In the position shown, the inlets 11 and 12 are connected by the manifold 14 to the port 17 which in turn communicates through the reversing valve with an oil admission port 23. This is joined by a duct 24 to the lower portion of a balancing tank 26. This tank is preferably spherical in contour and contains a body 27 of oil and a volume 28 of air.

Oil from the balancing tank 26 flows through the duct 24 and into the inlet of the main pump 8. In the position of the transfer or reversing valve shown, the pump outlet 13 is connected through the pipe 19 and the port 21 with an intermediate port 29 joined by a pipe 31 to a connection 32 at the lower end of the cylinder 6 beneath the piston therein. Thus, as the reversing valve is positioned in the illustration, oil is transferred from the body 27 and put under greater pressure beneath the piston within the cylinder 6. The piston is thus lifted.

As the piston rises, it eventually uncovers a line 33 previously subjected to substantially atmospheric pressure and suddenly subjects such line to the pumping pressure. There is consequently a communication of the higher pressure

through a check valve 34 and through a line 36 into an end connection 37 in a pilot valve generally designated 38. The pilot valve 38 is, because of the incidence of higher pressure on its enlarged end adjacent the connection 37, transferred or shifted to its opposite extreme position and diverts pressure oil from one of its two ports 39 and 40 into a line 42 leading to a control port 43 in the end of the reversing valve 18. This translates the shuttle 22 into its opposite extreme position. Discharge oil from the shuttle valve 38 flows through port 44 and 46 into a drain line 47. When the shuttle 22 is translated as described, the connections in the reversing valve are such that the connecting pipe 31 permits oil to leave the cylinder 6 as the piston therein descends and to return through the port 29 and the port 16 into the inlet 11 of the main pump 8. At the same time, the pump pressure port 21 is connected to the port 23 so that there is a return oil flow through the line 24 back to the balancing tank 26.

When the piston within the cylinder 6 descends to its lowermost position, it travels over a pipe 51 which previously has been subjected to pumping pressure but after it is passed by the piston, is subject to substantially atmospheric pressure. A check valve 52 in the lower end of the line 36 permits flow from such line into the cylinder above the piston and relieves the pressure on the end duct 37 of the shuttle valve 38. This valve then translates into its opposite axial position, as illustrated in the figure, and restores the connections to their previous arrangement so that the shuttle 22 of the main reversing valve also is restored. The parts are thus returned to the cycle beginning as previously described and the piston within the cylinder starts its upward stroke again. During the cycle, the pressure transferred through the port 43 of the reversing valve fluctuates between a low value and a high value. Also during the cycle, the translations of the shuttle valve and of the reversing valve and the operation of various other instrumentalities provide a small amount of oil which is released from high pressure to low pressure. This oil, known as scavenge oil, is returned to an appropriate point in the system joined to the drain line 47 leading ultimately into the balancing tank 26.

An oil reservoir or scavenge tank 56 is normally operated at substantially atmospheric pressure and is provided with an oil filter or breather 58 to keep out dust and unwanted atmospheric particles. Preferably, a scavenge line 57 extends below the normal oil level within the scavenge tank and passes through a check valve 59 and a normally closed hand control valve 60 to join the drain line 47. In addition, there proceeds from the scavenge tank 56 at a point above the oil level a second scavenge line 61 which passes through a check valve 62 into the drain line 47. Joining the drain line 47 is an overflow line 63 from a compression chamber 64 at the upper end of the cylinder and from which flows oil previously discharged onto the top of the reciprocating piston. Such oil flows through the line 63 into the drain line 47.

All of the accumulated material in the line 47 and its connections both liquid, such as oil, and gaseous, such as air, is drawn through the line 70 toward a scavenge pump 66 of the kind shown in Patent No. 2,575,241 of Ira Morgan White, above identified. This pump is mechanically driven and is effective to pump air, oil or a mixture thereof is varying quantities. The pump 66 forces such

mixture through a line 67 provided with a check valve 68 into a connection 69 preferably disposed at the top of the balancing tank 26. The oil and air are separated by gravity in the balancing tank. This constitutes the main return of scavenge oil and the supply of make-up air to the balancing chamber. The oil level therein is indicated by a sight glass 71.

The amount of oil which is returned through and by the pump 66 is a variable amount. In the initial starting of the system, the manual valve 60 is opened and sufficient oil from the sump tank 56 is withdrawn through the check valve 59 for charging the system. Subsequently, the valve 60 is closed and the line passing through it is therefore blocked. So that there will be adequate oil return through the line 63 and through the lines 44 and 46, the amount of air which passes through the line 61 is greatly restricted by an orifice 72. During the normal operation of the pump 66 a lower pressure exists within the line 47 and 61 than exists in the scavenge tank 56. In this fashion, residue oil is returned and some new air drawn in through the breather 58 and into the balancing tank.

For new oil to take the place of oil which is completely lost from the system and so does not flow through the scavenge pump 66, I provide an oil make-up and pressure control arrangement.

A body 81 is provided with a pair of cylindrical bores 82 and 83 of different diameters. Within the bore 82 there is reciprocably disposed a piston 84 having packing rings 85 and provided with a reduced collar 86 and a head 87. A cross passage 88 is drilled through the collar and a head opening 89 communicates with the cross passage. At its other end, the piston has an enlarged head 91 constituting a stop and a seat for a return coil spring 92 also resting against a shoulder 93 in the body 81. A closure cap 94 seals the upper chamber while a closure cap 96 seals the lower end of the body. An inlet port 97 is connected by a duct 98 to the line 57 while an outlet port 99 is connected by a duct 101 through a check valve 102 to the line 47. In addition, a port 103 is joined by a pipe 104 to a connection with the line 42 extending between the pilot valve and the reversing valve and once per cycle subject to a pressure fluctuation.

With this arrangement, as the reversing valve shuttle 22 reciprocates back and forth under the influence of fluctuating pressure in the line 42, this pressure is communicated in a cyclic fashion through the pipe 104 and the port 103 into the upper cylinder 83. When a high pressure is imposed upon the chamber, the effect is to displace the piston 84 downwardly compressing the spring 92 and causing the piston to overtravel the port 91. Oil within the volume of the bore 82 below the passage 88 is transferred by the reduction of such volume, through the passage 83 and into the port 99 and through the pipe 104 and check valve 102 into the return line 47. Oil within the chamber 82 is thus restored to the balancing tank.

When the reversing valve shifts its end position and the pressure in the line 42 is correspondingly dropped in a cyclic fashion, there is a similar reduction of pressure within the chamber 83. The spring 92 is then effective to restore the piston 84 to its original position. Normally this would, in enlarging the chamber 82, reduce the pressure within the line 101 but the check valve 102 prevents that and there is no back flow through the line 101.

The reduction in pressure is communicated

through the port 87 and the line 98 to the body of oil within the reserve or scavenge tank 56, the check valve 59 preventing back flow from the line 47. Atmospheric pressure forces reserve oil into the chamber 82 beneath the piston, charging the make-up pump for a subsequent stroke. When the reversing valve shuttle 22 is again reciprocated and pressure is again imposed upon the line 104, the piston 84 is driven downwardly again and another charge of make-up oil is transferred through 10 the scavenge pump 66 into the balancing tank 26. For each cycle or stroke of the main pumping jack 6, a definite or predetermined amount of additional, make-up oil is supplied to the balancing tank 26 through the operation of the piston 84.

The amount of make-up oil is initially determined to exceed any ordinary requirements. That being so, it is likely that an excessive amount of oil would eventually accumulate in the balancing tank 26. For that reason, I provide in the balancing tank and extending to a convenient height therein a standpipe or overflow pipe 111 connected through a hand shut-off valve 112 to a pressure regulator 113 in a return line 114 extending ultimately to the scavenge tank 56. An auxiliary blowdown line 116 controlled by a hand valve 117 is also provided.

In normal operation, the hand valve 117 is closed and the hand valve 112 is open and the pressure regulator 113 is set to relieve any pressure in excess of the desired amount. If the pressure within the balancing chamber 26 exceeds the desired value, such pressure causes a fluid flow (not necessarily liquid) through the pipe 111 and through the pipe 114 back to the scavenge tank. If the oil level in the body 27 is below the top of the standpipe 111, the fluid flow is air exclusively. The air travels into the scavenge tank 56 but is released through the breather 58 thereof to the atmosphere. If the body 27 of oil is excessive in amount and stands above the upper end of the pipe 111 when the excess pressure is relieved, then the flow through the pipe 111 is oil exclusively. The liquid then flows through the pipe 114 into the scavenge tank 56 and joins the body of oil therein for future make-up purposes. The pressure in the scavenge tank is always maintained at atmospheric value because of the breather 58.

If the level of oil 27 fluctuates near the top of the overflow standpipe, then a combined discharge of oil and air may take place through the lines 111 and 114 until the pressure drops to a value permitting the valve 113 to close and stop the flow. Any air oil mixture flowing through the pipe 114 travels into the scavenge tank 56 and by gravity separates therein, the oil being retained in the general sump or body of oil therein while the air escapes through the breather 58 to the atmosphere.

By the provision of this structure, therefore, I have provided a make-up oil pump which is effective once a cycle to transfer from a reservoir of oil a predetermined volume or quantity of oil into the balancing tank. I likewise provide a means for maintaining the fluid pressure within the balancing tank at exactly the desired value and for releasing from that tank not only any air that causes excessive pressure but likewise any excessive oil. There is always retained within the balancing tank a minimum or pre-determined amount of oil at a set level. No air is released below the desired pressure. With this arrangement, the scavenge pump 66 takes care of the return of variable flows or amounts of oil which are

used and released to low pressure parts of the system during normal operation and supplies make-up air whereas the make-up oil pump introduces to the system new oil to make up for losses due to packing leakage, spillage and the like.

What is claimed is:

1. A pumping jack oil make-up and pressure control comprising a balancing tank adapted to contain oil and air, a jack cylinder, a piston reciprocable in said cylinder, a first pump for transferring oil between said jack cylinder and said tank, a valve responsive to the position of said piston in said jack cylinder for regulating the direction of said oil transfer, a second oil pump, means for operating said second oil pump in time with and in response to the operation of said valve, an oil reservoir, oil conduits between said reservoir and said second oil pump and between said second oil pump and said balancing tank, and an oil overflow pipe disposed with one end at a predetermined level in said balancing tank and extending between said balancing tank and said reservoir.
2. A pumping jack oil make-up and pressure control comprising a balancing tank adapted to contain oil and air, a jack cylinder, a piston reciprocable in said cylinder, a first pump for transferring oil between said jack cylinder and said tank, a reciprocating valve, means responsive to the position of said piston in said jack cylinder for reciprocating said valve in accordance with the reciprocation of said piston for regulating the direction of said oil transfer, a second oil pump, means for operating said second pump in response to the operation of and in accordance with the reciprocation of said valve, an oil reservoir, oil conduits between said reservoir and said second oil pump and between said second pump and said balancing tank, an oil overflow pipe disposed with one end at a predetermined level in said balancing tank and extending between said balancing tank and said reservoir, and a pressure regulator in said overflow pipe.
3. A pumping jack oil make-up and pressure control comprising a balancing tank adapted to contain oil and air, a jack cylinder, a piston reciprocable in said cylinder, means for cyclically transferring oil from said balancing tank to said cylinder and vice versa, an oil sump tank, a reciprocating oil pump, an inlet line connected to said oil sump tank and to said oil pump inlet, an outlet dust connected to the oil pump outlet and to said balancing tank, and means for reciprocating said oil pump through one cycle each time said cyclically transferring means transfers oil from said balancing tank to said cylinder and vice versa.
4. A pumping jack oil make-up and pressure control comprising a balancing tank adapted to contain oil and air, a jack cylinder, a piston reciprocable in said cylinder, a first pump for transferring oil between said jack cylinder and said tank, a valve for controlling the direction of the oil transfer, means responsive to the position of said piston in said cylinder for actuating said valve, an oil sump tank, a reciprocating oil make-up pump, conduits connecting the inlet of said make-up pump to the oil in said sump tank and the outlet of said make-up pump to said balancing tank, and means responsive to the operation of said valve for reciprocating said oil make-up pump.
5. A pumping jack oil make-up and pressure control comprising a balancing tank adapted to contain oil and air, a jack cylinder, a piston re-

7
ciprocable in said cylinder, a first pump for transferring oil between said jack cylinder and said tank, a valve responsive to the position of said piston in said cylinder for controlling the direction of the oil transfer, a sump tank, a conduit for carrying oil from said valve to said sump tank, a scavenge pump, an outlet from said scavenge pump to said balancing tank, a conduit for transferring oil from said sump tank to the inlet of said scavenge pump, a duct for carrying air to the inlet of said scavenge pump, a make-up pump for transferring oil from said sump tank to said balancing tank, an overflow pipe from said balancing tank to said sump tank, and a pressure regulator in said overflow pipe.

6. A pumping jack oil make-up and pressure control comprising a balancing tank adapted to contain oil and air, a jack cylinder, a piston reciprocable in said cylinder, a first pump for transferring oil between said jack cylinder and said tank, means responsive to the position of said piston in said cylinder for controlling the direction of the oil transfer, an oil make-up pump, means for driving the make-up pump by the transfer oil and in response to the direction of 25

8
the transfer, means for supplying said make-up pump with oil, and means for conducting oil from said make-up pump to said balancing tank.

5 7. A pumping jack oil make-up and pressure control comprising a jack cylinder, a piston reciprocable in said cylinder, means for supplying said cylinder with oil under pressure to reciprocate said piston cyclically, an oil make-up pump driven by said oil under pressure in time with the reciprocation of said piston, a source of oil, a conduit for conducting oil from said source of oil to said make-up pump, and a conduit for conducting oil from said make-up pump to said supplying means.
